UNITED STATES PATENT OFFICE.

HORACE B. McCABE, OF CHICAGO, ILLINOIS, ASSIGNOR TO GISHOLT MACHINE COMPANY, OF MADISON, WISCONSIN, A CORPORATION OF WISCONSIN.

TIME CONTROLLED ELECTRIC SWITCH AND RECORDING REGISTER.

1,117,213.

Specification of Letters Patent.

Patented Nov. 17, 1914.

Application filed July 30, 1913. Serial No. 781,922.

To all whom it may concern:

Be it known that I, HORACE B. McCABE, a citizen of the United States, residing at Chicago, in the county of Cook and State 5 of Illinois, have invented certain new and useful Improvements in Time Controlled Electric Switches and Recording Registers, of which the following is a specification.

My invention relates to time controlled 10 electric switches and recording registers and is in the nature of an improvement upon the apparatus described in my pending application on time controlled switch mechanism for electric circuits, filed October 10, 1912, 15 Serial Number, 724,910; and the apparatus described in United States Letters Patent, No. 1,063,272, issued to me June 3, 1913, for improvements in time recording reg- 20 isters.

The primary object of my invention is 25 the provision of improved mechanism of this character which shall have improved means for limiting the action of portions of the register and for indicating upon the record made by the register that the limiting means are in operation.

With the above and other objects in view 30 this invention consists substantially in the combination, arrangement and construction 35 of parts, all as hereinafter described, shown in the accompanying drawings, which form a part of this specification and show the preferred embodiment of my invention, and more specifically set forth in the subjoined 40 claims.

In the drawings: Figure 1 is a front elevation of the time controlled switch portion of my invention. Fig. 2 is a side elevation of the apparatus illustrated in Fig. 40 1. Fig. 3 is a top plan view of a portion of the apparatus illustrated in Figs. 1 and 2, having the upper part of the frame work broken away for clearness. Fig. 4 is a horizontal section taken on the line 4—4 of Fig. 45 1 and looking in the direction indicated by the arrows. Fig. 5 is a side elevation of that part of my invention illustrated above the line 4—4 of Fig. 1. Fig. 6 is a view similar to Fig. 5, showing a different disposition of some of the parts. Fig. 7 is a detent forming part of the mechanism illustrated in the preceding figures. Fig. 8 illustrates a shift lever forming a 50 part of the mechanism illustrated in Figs. 1 to 6 and shows a portion of the detent

illustrated in Fig. 7 in its position with relation to the shift lever. Fig. 9 is a detached view of parts of my invention shown in side elevation in Fig. 2 combined with a diagram of portions of an electric circuit connected thereto. Fig. 10 is a view of the reverse side of a part of the apparatus shown in Fig. 9. Fig. 11 is a view in perspective of that portion of the apparatus illustrated in Figs. 9 and 10. Fig. 12 is a detached view of portions of the apparatus shown in front elevation in Fig. 1, and illustrates in dotted lines an adjusted position of the parts. Fig. 13 is a horizontal section taken on the line 13—13 of Fig. 12 and looking in the direction indicated by the arrows. Fig. 14 is a rear elevation of the time controlled recording register portion of my invention, some of the parts thereof being illustrated in section on the line 14—14 of Fig. 15, looking in the direction indicated by the arrows. Fig. 15 is a section taken on the line 15—15 of Fig. 14, looking in the direction indicated by the arrows and showing in dotted lines a different position of some of the parts; this figure is combined with a diagram of parts of an electric circuit connected with the apparatus. Fig. 16 is a partial view of Fig. 14 illustrating the position of parts thereof shown in Fig. 17 and having some of the parts sectioned along the line 16—16 of Fig. 17. Fig. 17 is a section taken on the line 17—17 of Fig. 16. Fig. 18 is a perspective view of an oscillating collar and its attached parts shown in various ways in Figs. 14 to 17 inclusive. Fig. 19 is a view in perspective of one of the ratchet wheels illustrated in Figs. 14 to 17 inclusive. Fig. 20 illustrates a record such as produced by the present invention.

In my pending application above referred to means are disclosed for periodically closing and opening an electric circuit and for pre-determining intervals during which the periodic closing and opening shall be arrested. In conjunction with means for performing those two functions, means are also disclosed for rendering the periodic closing and opening means operative during pre-determined inoperative intervals, including a manually operated shift lever by means of which such adjustment of parts is secured as to accomplish this third function.

A plurality of indicating or number

110

wheels periodically actuated are disclosed in the patent above referred to on improvements in time recording registers, these indicating wheels being changed periodically 5 and consecutively. In fact, in practice they constitute a form of cyclometer. Apparatus is also shown, manually operable, for idling certain of the indicating wheels of the register while continuing the periodic consecutive 10 change of others of the indicating wheels.

The present invention, among other things, combines the apparatus disclosed in the above mentioned pending application 15 with the apparatus constituting the subject matter of the above mentioned patent into one co-acting machine and provides means whereby the manually operated shift lever, through co-action with the idling apparatus 20 in the register, causes it to be operative or inoperative. Besides governing the operation of the idling mechanism in the register the throw of the shift lever likewise provides for the insertion in the line of 25 printing type of the register of a character which indicates upon the record taken from the register that the idling mechanism is in operative position.

In Fig. 2 of the drawings reference numeral 20 indicates a wall to which is secured a frame plate 21, the members 20 and 21, together with supporting arms 22, representing any suitable means for supporting time controlled electric switch mechanism 30 and for supporting a clock movement indicated generally by A but not illustrated in detail. The frame work for the switch mechanism portion of my invention is indicated by reference numeral 23 and is adapted to support the various parts of the mechanism in their proper positions.

Suitably mounted upon a horizontal pivot post 24 secured in the frame 23 are two pivoted blocks of insulating material 25 and 26 which carry respectively electricity conducting switch arms 27 and 28, bearing one the female portion 31, the other the male portion 32, of an adjustable circular knife switch upon their forward ends. The switch arms 27 and 28 extend rearwardly of the insulating blocks 25 and 26 and bear upon their rearward extremities a carbon make-and-break device including two carbon blocks 29 and 30, which, by contacting 55 with each other before the closing of the knife switch and by separating from each other after the opening of the knife switch, serve to protect the knife switch from arcing. The specific construction of this switch 60 is set forth in the previously mentioned pending application on time controlled switch mechanism for electric circuits, and for that reason is not here inserted.

The switch arms 27 and 28 are preferably 65 secured to the upper surfaces of the insu-

lating blocks 25 and 26 and to their lower surfaces are secured two rider arms 33 and 34 of slightly different lengths and extending forwardly of the insulating blocks. The rider arms 33 and 34 ride upon the periphery of a ratchet wheel 35 rotated directly by the clock A. The passing of the points of the ratchet wheel 35 moves the rider arms in such manner as to close and open the knife switch above described at the passage beyond the ends of the rider arms 23 and 24 of each point. In this manner the knife switch is normally actuated to close and open an electric circuit periodically. Details of this periodic closing and opening mechanism are set forth in the above mentioned pending application on time controlled switch mechanism for electric circuits and for that reason are not given here.

A swinging detent lever 36, weighted at 85 one of its ends as at 37, is suitably supported by the frame work 23 and has a normal tendency during the upper position of the rider arm 34 to catch that rider arm and withhold it from its normal periodic 90 switch closing and opening action. A twenty-four hour cam wheel 38, suitably journaled on the frame work 23 and provided with a plurality of adjustable cams about its periphery is rotated by the clock 95 A, and a rider post 39 rigidly secured to one end of the swinging detent 36 mounts and rides upon the cams of the wheel to withhold the detent from contact with the rider arm 34. Normally the rider post 39 100 rides upon adjustable cams 40, 41, 42, and 43, which cams lie close to the plane of the cam wheel and preferably contact with it on one side or the other. Another adjustable cam 44 rotates with the twenty-four 105 hour cam wheel 38 but is spaced somewhat therefrom in order that it shall normally clear the free end of the rider post 39. By adjustment of the cams 40, 41, 42, and 43 upon the wheel 38 various portions of the 110 circumference of the wheel 38 may be left without cam surfaces, and during the passage of these uncammed portions of the circumference of the wheel 38 past the rider post 39, the rider post, having nothing to 115 support it, falls, allowing the swinging detent 36 to catch the rider arm 34 and thus arrest the switch arm 28 from its normal action of periodically closing and opening an electric circuit. In this manner are pre-determined certain portions of the day during which the normal closing and opening of an electric circuit by means of the switch is arrested. A specific description 120 of the pre-determining arresting mechanism just described forms part of my pending application on time controlled switch mechanism for electric circuits previously mentioned and is, therefore, omitted here.

The swinging detent 36 is shiftable within 125

limits in a direction at right angles to the plane of rotation of the cam wheel 38. Normally it is in a position to mount and ride upon the cams 40, 41, 42, and 43 and to clear the spaced cam 44. It may be shifted, however, by means of its connection with a manually operable shift lever 45, handled for convenience as at 46 and provided with a bifurcated, off-set inner end 47, to a position 5 wherein it will mount and ride upon the spaced cam 44—the bifurcated end 47 being disposed about the detent lever 36 to actuate it, and the shift lever 45 being pivoted intermediate its ends as at 48. Normally 10 the spaced cam 44 clears the outer end of the rider post 39, making the knife switch inoperative during the passage by the rider post of the uncammed portion of the cam wheel 38 lying between the cams 43 and 40; 15 in other words, the period during which that uncammed portion of the wheel 38 is passing the rider post 39 constitutes one of the pre-determined inoperative intervals of the switch mechanism. By movement of the 20 shift lever 45, however, and consequent shifting forward of the rider post 39, the post may be made, during this pre-determined inoperative interval, to mount and ride upon the spaced cam 44, thus rendering 25 operative the periodic closing and opening function of the switch during pre-determined inoperative intervals. A more minute 30 description of the means for making the periodic closing and opening switch operative during pre-determined inoperative intervals is set forth in the above mentioned pending application on time controlled 35 switch mechanism for electric circuits.

In the present invention a block of insulating material 49 (see Figs. 9 to 12 inclusive) is secured to the frame work 23 and carries upon one of its sides and adjacent the top two binding posts 50 and 51. The block 49 also carries upon its opposite side and 40 adjacent the bottom a pair of binding posts 52 and 53. Any means for energizing an electric circuit with a direct current of electricity, such as an electric battery, is indicated at B in Fig. 9, and the terminals 54 and 55 of the battery are connected respectively to the binding posts 50 and 51 of the block 49. The block 49 is attached to the frame work at one of its ends and upon the opposite end it carries four switch point 45 arms 56, 57, 58, and 59, which carry respectively the adjustable switch points 60, 61, 62, and 63, these switch points being preferably in the form of screws threaded into the switch point arms. The binding post 52 is electrically connected to the switch arm 27 by means of a preferably flexible conductor 64, and similarly, the binding post 53 is electrically connected to the switch arm 28 by means of another flexible conductor 55 60 65. An electrical conductor 66 connects the

binding posts 50 and 52, the binding post 52 extending through the block 49 into threaded engagement with the lower end of the conductor 66. The switch point arms 57 and 59 are somewhat longer than the switch point arms 56 and 58, and the switch points 60, 61, 62, and 63 are preferably so positioned as to lie in the same horizontal plane and be disposed with their contact points all between the vertical planes of the respective 70 switch point arms, that is, the points 60 and 61 project toward the points 62 and 63, and the points 62 and 63 project toward the points 60 and 61. The binding post 51 secures to the block 49 both the long upper 75 switch point arm 57 and the short upper switch point arm 58, likewise joining them electrically, and similarly, the binding post 53 secures to the block 49 both the long lower switch point arm 59 and the short lower 80 switch point arm 56, as well as joining these two arms electrically. Upon a pin 67 horizontally secured at one end to the frame 23 is pivoted an insulating block 68 which carries adjacent one of its ends two spaced reversing arms 69 and 70, which extend upwardly parallel with each other, and are adapted to contact simultaneously either with the pair of switch points 60 and 61 or the pair of switch points 62 and 63 according as they are pivotally actuated. The means for actuating the reversing arms comprises a downwardly extending bar 71 upon the end of the block 68 opposite the end to which the reversing arms are secured, a connecting link 72 upon the lower end of the bar 71, and an arm 73 formed upon the shift lever 45 and to which the other end of the connecting link 72 is joined. In Figs. 12 and 13 are shown two positions of the reversing arms 69 and 70, and the reversing mechanism just described, one of the positions being shown in full lines and the other in dotted lines. By this construction the shifting of the shift lever 45, besides adjusting the rider post 39 into such position that it will make the periodic closing and opening switch mechanism operative during pre-determined inoperative intervals, will also move the reversing arms 69 and 70 from contact respectively with the switch points 60 and 61 across to contact respectively with the switch points 62 and 63. Electric conductors 74 and 75 are attached respectively to the reversing arms 69 and 70 and afford electric communication between those arms and the time recording register portion of my invention. The direct current of electricity from the battery B is, by means of the mechanism just described, caused to flow in one direction or in the opposite direction according as the shift lever 45 is at one end or the opposite end of its path of shift.

In the patent numbered 1,063,272 on improvements in time recording registers a

plurality of indicating wheels 76, 77, 78, and 79 are respectively mounted upon and have rotation with concentric shafts 80, 81, 82, and 83, the shafts being rotated by ratchet wheels 84, 85, 86, and 87 respectively. The ratchet wheels 84, 85, and 86 are provided respectively with side disks 88, 89, and 90. These side disks are of different diameters and are each notched at one point of the periphery for engagement with an actuating pawl 91 which operates the ratchet wheels 84, 85, 86, and 87 consecutively and consequently changes the indicating wheels 76, 77, 78, and 79 consecutively, the action of this mechanism being virtually that of the ordinary cyclometer. For the purpose of clearness the ratchet wheel 85 and its side disk 89 are illustrated in perspective in Fig. 19. The pawl 91 is prevented by the disk 88 from actuating any of the ratchet wheels except 84 until the pawl comes to the notched point of the side disk 88 when the notch therein allows the pawl to drop sufficiently to engage the teeth of the ratchet wheel 85. Similarly the side disk 89 upon the ratchet wheel 85 prevents the pawl 91 from falling sufficiently to engage the ratchet wheel 86 until the notched portion of the side disk 89 is presented to the pawl, at which time the pawl is allowed to drop sufficiently to engage the ratchet wheel 86. The same action is true of the side disk 90 upon the ratchet wheel 86 with reference to the action of the pawl 91 upon the ratchet wheel 87, the ratchet wheel 87 not being actuated by the pawl until the notch of the side disk 90 is in engagement with the pawl 91. The pawl 91 has a path of movement shown in Fig. 15 by full lines and dotted lines. It is actuated in this path of movement by means of an electro-magnet 92 electrically connected to the conductors 74 and 75, a plate 93 forming an armature for the magnet, and a lever 94 secured to the plate 93. A spring member 95 actuates the lever 94 to move the pawl 91 normally into the position shown in dotted lines in Fig. 15, while the electro-magnet 92 periodically moves the lever 94 to draw the pawl 91 into the position shown in full lines in Fig. 15. The above mentioned portions of my time recording register, as well as its frame 96, being minutely described in the above mentioned patent a more specific description of them is here omitted.

In the present invention a collar 97 is disposed for oscillation about the shaft 80. At one of its ends this collar is provided with a cam 98 so placed that in one position of the collar the cam is operative to withhold the pawl 91 from dropping into the notch of the side disk 89 and engaging the ratchet wheels 86 or 87. Normally the cam 98 is in an inoperative position with respect to the pawl 91—the operative position of the

cam being shown in Figs. 14 and 15 and the inoperative position thereof in Figs. 16 and 17. When the cam 98 is inoperative the pawl 91 is free under the action of the electro-magnet 92 to perform its normal function of changing the indicating wheels 76, 77, 78, and 79, but when the cam is in its operative position the pawl 91 is withheld by contact with the cam from changing any but the indicating wheels 76 and 77. Adjacent the opposite end of the collar 97 from that upon which the cam 98 is mounted is secured an indicating character 99 such as the letter X shown most clearly in Fig. 18. This indicating character 99 is so set upon the collar that when the cam 98 is in the operative position shown in Figs. 14 and 15 the indicating character 99 will assume a position in the indicating or printing line of the indicating wheels 76, 77, 78, and 79; this position of the indicating character 99 being shown in dotted lines in Fig. 14 and in full lines in Fig. 15. When, however, the cam 98 is in an operative position, as illustrated in Figs. 16 and 17, the indicating character 99 assumes a position outside of the indicating or printing line of the wheels 76, 77, 78, and 79, as is shown in dotted lines in Fig. 16 and in full lines in Fig. 17. The collar 97 is also provided preferably adjacent its cammed end with a power arm 100 which at its free end is joined to a connecting rod 101, the other end of the connecting rod being attached to an armature lever 102. Secured in suitable position to the frame 100 work 96 is a polarized magnet generally indicated by C. The polarized magnet may be of any suitable type, the one preferred and illustrated in the drawings comprising a permanent magnet 103, the poles of which are indicated at 104 and 105. A yoke 106 is secured to the pole 104 and is upbent at one end as 107 for convenience in attaching the polarized magnet C to the frame 96. To the yoke 106 are secured two soft iron cores 108 and 109, about which are disposed respectively electric coils 110 and 111. These coils are electrically joined as at 112, and the conductor 75 is connected to the coil 110 while the conductor 74 is connected to the coil 111. To the pole 105 of the permanent magnet 103 is secured a bearing 113 in which is mounted a shaft 114 carrying a soft iron armature 115 in such position that the side surface of the armature faces the pole of the permanent magnet, leaving a slight air gap between. Opposite the ends of the soft iron cores 108 and 109 the armature 115 is bent into contacting arms 116 and 117. The armature lever is rigidly secured to the soft iron armature 115 by any suitable means such as the cap screws 118. By this construction the movement of the armature 115 is communicated to the armature lever 102 and thence to the cam 98 and the indicating 130

character 99. In the present exemplification of my invention the polarized magnet C is shown connected to the conductors 74 and 75 in parallel with the electro-magnet 92, but such connection is not essential, for the same results may be obtained if the electro-magnet 92 and the polarized magnet C are connected to the conductors 74 and 75 in series, the electro-magnet 92 being operable 10 to perform its function regardless of the direction of flow of current in the conductors 74 and 75. The direction of flow of current in the conductors 74 and 75 governs the action of the polarized magnet C and consequently 15 the positioning of the cam 98 and the indicating character 99. The direction of flow of current in the conductors 74 and 75 is governed by the position of the reversing arms 68 and 70, 20 and the position which they occupy is in turn controlled by the location of the shift lever 45 at one end or the other of its path of shift.

In the use of my invention it is desirable 25 at times to cause periodic closing and opening of the electric circuit described during pre-determined inoperative intervals, and when such action of the apparatus is desirable it is also necessary to interpose in the 30 indicating or printing line of the indicating wheels some character which shall show clearly that the electric circuit is being periodically closed and opened during a pre-determined inoperative interval. In practice 35 during the normal working hours of the day the electric circuit is periodically closed and opened. The pre-determined inoperative intervals represent normally the noon hour or the night space between the 40 close of normal working hours in the evening and the commencement of normal working hours the next morning. When men are to be employed in overtime work, the shift lever 45 and the reversing arms 69 45 and 70 are thrown into the position shown in full lines in Figs. 12 and 13, which simultaneously places the rider post 39 in position to mount and ride upon the spaced cam 44. Being upon the spaced cam 44 during 50 a pre-determined inoperative interval, the rider post will withhold the detent 36 from contact with the rider arm 34 and allow the switch members 32 and 31 to meet and separate periodically. During the normal 55 working hours the reversing arms 69 and 70 are in contact respectively with the contact points 60 and 61, which cause the electric current to pass through the conductors 74 and 75 in such a direction that the contact member 117 of the polarized magnet C 60 will be drawn to engagement with the soft iron core 109, thus throwing the cam 98 and indicating character 99 into the position illustrated in Figs. 16 and 17; namely, into 65 their inoperative positions. When, how-

ever, by the shifting of the shift lever 45 into the position shown in full lines in Fig. 13 the reversing arms 69 and 70 are thrown across into contact respectively with the contact points 62 and 63, the direction of flow of current through the conductors 74 and 75 is reversed from that traversed during normal working hours, causing the contact member 116 to be attracted to the core 108, and throwing the cam 98 and the indicating character 99 into the operative positions shown in Figs. 14 and 15.

When in their operative positions the indicating character 99 assumes a place in the indicating or printing line of the indicating 80 wheels 76, 77, 78, and 79 while simultaneously the pawl 91, contacting with the cam 98, is allowed to actuate only the ratchet wheels 84 and 85 and their respective indicating wheels 76 and 77, leaving idle the 85 ratchet wheels 86 and 87 and their respective indicating wheels 78 and 79. At the close of the normal working hours of the day a definite number of hour periods are indicated by the indicating wheels 76, 77, 78, 90 and 79, which number, under normal conditions, would remain in indicating position in the register until the beginning of normal working hours the following morning, the periodic closing and opening of the electric 95 circuit being normally arrested during that period. But when it is desired to employ the apparatus in indicating overtime during the night, the amount of time worked will ordinarily be somewhat less than the 100 number of time units represented by one complete cycle of the indicating wheels 76 and 77; it being the practice in the use of my present invention to actuate the indicating wheels once every tenth of an hour. Under 105 this practice something less than one hundred of such time periods would represent the ordinary amount of time consumed in overtime work at night in a factory. For this reason the spaced cam 44 is constructed 110 of such a length that it will cause the periodic closing and opening of the electric circuit during exactly one hundred periods. It is obvious then that if only the indicating 115 wheels 76 and 77 are actuated during the period of overtime work and if the indicating wheels 78 and 79 are idle during that time, the number of hour periods indicated at the end of the overtime period will be identical with the number indicated at the 120 beginning of that period.

At the close of the normal working hours of the day the periodic closing and opening of the electric circuit is automatically arrested by the falling of the rider post 39 from the cam 40. When it is proposed to work overtime during the night the operator in charge moves the shift lever 45 into the position shown in full lines in Fig. 13. This shift of the lever causes a reversal in the 125 130

direction of flow of current in the conductors 74 and 75, a throw of the armature 115 into the position shown in Fig. 15, and the placing in operative position of the cam 98 and the indicating character 99. Being in this operative position the cam 98 allows the pawl 91 to actuate only the indicating wheels 76 and 77 which, it is to be understood, are the units and tens wheels of the set. In practice, and regardless of the shortness of the overtime period worked, the rider post 39 is allowed to ride upon the cam 44 for the full length of the cam, which will cause one hundred changes of the indicating wheels 76 and 77 and leave them, when the rider post falls from the cam 44, in the same position they occupied at the close of the preceding normal working hours. Between the time when the rider post 39 falls from the cam 44 and the commencement of normal working hours the following morning the operator changes the shift lever 45 into the position shown in dotted lines in Fig. 13, which reverses the direction of flow of current in the conductors 74 and 75 and causes a shift of the cam 98 and indicating character 99 to their inoperative positions, as illustrated in Figs. 16 and 17. When the men who work during the normal working hours of the day resume their work the following morning after an overtime night period has been worked, the cards which they print in the recording register will show the same number at the beginning of the normal morning working hours that they did at the close of the previous day's normal working hours. Consequently, if a workman began a piece of work at three o'clock in the afternoon of one day and the record printed by him upon his job card was, for example, 1212, and if he ceased work upon that job at the close of normal working hours that day, say six o'clock, and resumed work upon that job the following morning at the commencement of normal working hours, say seven o'clock, and worked for two hours on that same job in the morning, or until nine o'clock, the number printed by him at nine o'clock upon his job card would be 1262, and the difference between this number and that which he printed when he began the job would show exactly the number of time units or tenth hour periods worked on that job regardless of whether or not the apparatus of this present invention has been employed to record overtime during the intervening night period. The job cards printed during the overtime period (the normally inoperative period of the periodic closing and opening switch) would each show, in addition to the characters normally printed upon a job card, the impression of the indicating character 99, which would illustrate clearly to the clerk handling the cards that the record made upon them was a record of

overtime and not a record of normal working time.

The action of the polarized magnet C is such that it will remain stationary in the position it assumes during the flow of the current in a given direction until such time as the direction of flow of the current is reversed; when it will assume its opposite position. Thus the periodic energizing of the electro-magnet 92 by the periodic closing and opening of the circuit during normal working hours will have no reversing effect upon the polarized magnet C, the direction of flow of the current through the conductors 74 and 75 being uniform during normal working hours. Similarly, when the shift lever 45 has been thrown into the position indicated in full lines in Fig. 13 the polarized magnet, though reversed from the position it occupies during normal working hours, will remain in its reversed position throughout the period of such shift of the lever 45 for the reason that the flow of current during that period is constant in the reverse direction.

In the accompanying drawings and in the foregoing description is set forth the preferred embodiment of my invention, but it is obvious that one skilled in the art may make modifications thereof without departing from the spirit of the invention.

I claim:

1. The combination of a plurality of indicating and printing wheels, time controlled means for periodically actuating said wheels, time controlled means for arresting said periodic actuation during predetermined intervals, and means for simultaneously causing the periodic actuation during said predetermined intervals and limiting it to certain of the wheels only.

2. The combination of a plurality of indicating and printing wheels, time controlled means for periodically actuating said wheels, time controlled means for arresting said periodic actuation during predetermined intervals, and means for simultaneously causing the periodic actuation during said predetermined intervals, limiting it to certain of said wheels only, and inserting in the indication or print made by the wheels an additional character.

3. The combination of a plurality of indicating and printing wheels, time controlled means for periodically actuating said wheels, time controlled means for arresting said periodic actuation during pre-determined intervals, and means for simultaneously causing said periodic actuation during said pre-determined intervals and inserting in the indication or print made by the wheels an additional character.

4. The combination of a plurality of indicating and printing wheels, time controlled means for periodically actuating said

wheels, and means for simultaneously limiting said periodic actuation to certain of the wheels only and inserting in the indication or print made by the wheels an additional character.

5. The combination of a plurality of indicating and printing wheels, an electric circuit, time controlled electrical means in the circuit for periodically actuating said 10 wheels, time controlled means for arresting said periodic actuation during pre-determined intervals, means for causing the periodic actuation during the pre-determined intervals, and electrical means interposed in the circuit for limiting the periodic actuation during said pre-determined intervals to certain of said wheels only.

6. The combination of a plurality of indicating and printing wheels, a plurality of 15 ratchet wheels connected to the indicating and printing wheels for operating them, a movable pawl for actuating the ratchet wheels, a source of supply of direct current 20 electricity, an electro-magnet connected to the source of supply for actuating the pawl, time controlled means for periodically energizing the magnet, time controlled means for arresting the periodic energizing during 25 pre-determined intervals, means for causing 30 said energizing during the pre-determined intervals, a shiftable member for placing in operative position said time controlled means for causing the periodic energizing 35 during the pre-determined intervals, means 40 for limiting the action of the pawl to certain of the indicating and printing wheels only, a polarized magnet connected with the source of supply and the armature of which is connected to the limiting means to actuate them, and a current reversing device for operating the polarized magnet, said reversing device being connected with the shiftable member and operated thereby.

7. The combination of a plurality of indicating and printing wheels, a source of supply of direct current electricity, an electro-magnet connected to the source of supply for actuating said wheels, time controlled means for periodically energizing the electro-magnet, time controlled means for arresting said periodic energizing during pre-determined intervals, an oscillating member 50 for limiting the action of the electro-magnet to certain of said wheels only, a polarized magnet connected to the source of supply and the armature of which is connected to the oscillating member to actuate it, and means for simultaneously causing the periodic actuation of the electro-magnet during 55 said pre-determined intervals and placing the oscillating member in operative position.

8. The combination of a plurality of indicating and printing wheels, a source of 60 supply of direct current electricity, an elec-

tro-magnet connected to the source of supply for actuating said wheels, time controlled means for periodically energizing the electro-magnet, time controlled means for arresting said periodic energizing during pre-determined intervals, an oscillating member for limiting the action of the electro-magnet to certain of said wheels only, a polarized magnet connected to the source of supply and the armature of which is connected to the oscillating member to actuate it, and means for simultaneously causing the periodic actuation of the electro-magnet during 70 said predetermined intervals and placing the oscillating member in operative position comprising a shift lever for placing in operative position the time controlled means for periodically energizing the electro-magnet, and a current reversing device connected to the shift lever and operated thereby for reversing the direction of flow 75 of electricity between the source of supply and the polarized magnet.

9. The combination of a plurality of indicating and printing wheels, time controlled means for actuating said wheels, time controlled means for arresting the actuation of said wheels during pre-determined intervals, an oscillating shaft, a cam upon the shaft and movable thereby into contact with the time controlled means for actuating the wheels to limit said means to actuation of certain of said wheels only, an indicating and printing character upon the oscillating shaft and movable thereby into the indicating and printing line of said wheels simultaneously with the movement into operative position of the cam, and means for simultaneously oscillating the shaft, and causing the actuation of the time controlled 90 wheel actuating means during said pre-determined intervals.

10. The combination of a plurality of indicating and printing wheels, time controlled means for actuating said wheels, time controlled means for arresting said actuation during pre-determined intervals, an oscillating shaft, an indicating and printing character upon the shaft and movable thereby into the indicating and printing line 100 of said wheels, and means for simultaneously oscillating the shaft and causing the actuation of the time controlled wheel actuating means during said pre-determined intervals.

11. The combination of a plurality of indicating and printing wheels, time controlled means for actuating said wheels, an oscillating shaft, a cam upon the shaft and movable thereby into contact with the time controlled means for actuating the wheels to limit said means to actuation of certain of said wheels only, an indicating and printing character upon the oscillating shaft and movable thereby into the indicating and printing line of said wheels simultaneously 115 with the movement into operative position of the cam, and means for simultaneously oscillating the shaft and causing the actuation of the time controlled wheel actuating means during said pre-determined intervals.

- ously with the movement into operative position of the cam, and electrically actuated means for oscillating the shaft.
12. The combination of a plurality of indicating and printing wheels, mechanical means for actuating said wheels, a source of supply of direct current electricity, an electro-magnet connected to the source of supply for operating the mechanical actuating means and operable when energized regardless of the direction of flow of electricity, time controlled means for energizing the electro-magnet, time controlled means for arresting the energizing during pre-determined intervals, means movable into contact with the mechanical wheel actuating means for limiting them to actuation of certain of the wheels only, a polarized magnet having a pivoted armature and connected with the source of supply, said armature being movable by reversal of the direction of flow of electricity through the polarized magnet, a current reversing device interposed between the source of supply and the polarized magnet, means for causing the energizing of the electro-magnet during said pre-determined intervals, and a shift lever connected to the last said means and to the current reversing device for operating them simultaneously.
13. The combination of a cyclometer, time controlled actuating means therefor, and electrical means for limiting the operation of the actuating means to certain wheels only of the cyclometer.
14. The combination of a cyclometer, time controlled actuating means therefor, and electrical means for limiting the operation of said actuating means to the first two wheels of the cyclometer only.
15. The combination of a cyclometer, time controlled actuating means therefor, and
- means for automatically limiting the operation of said actuating means to the first two wheels of the cyclometer only during one cycle of the second wheel.
16. The combination of a cyclometer, time controlled means for periodically actuating the cyclometer, time controlled means for arresting the periodic actuation during pre-determined intervals, means for causing the periodic actuation during said pre-determined intervals, and electrical means for limiting the periodic actuation during said pre-determined intervals to the first two wheels only of the cyclometer.
17. The combination of a cyclometer, time controlled means for periodically actuating the cyclometer, time controlled means for arresting the periodic actuation during pre-determined intervals, means for causing the periodic actuation during said pre-determined intervals, and electrical means for limiting the periodic actuation during said pre-determined intervals to the first two wheels only of the cyclometer during one cycle of the second wheel.
18. The combination of a cyclometer, time controlled actuating means therefor, and means for idling certain of the wheels of the cyclometer during a given interval and automatically resuming the actuation of the idled wheels when the number indicated by the cyclometer at the beginning of the given interval again appears.
- In testimony whereof I have signed my name to this specification, in the presence of two subscribing witnesses, on this 28th day of July, A. D. 1913.
- HORACE B. McCABE
